REGULATING DEVICE FOR ELECTROMAGNETIC DRIVEN VIBRATORY PENDULUMS

Curt Fredrik Ahlberg, Appelviken, Sweden, assignor to Telefonaktiebolaget L M Ericsson, Stockholm, Sweden, a company of Sweden

Application October 23, 1943, Serial No. 623,949
In Sweden November 18, 1944

3 Claims. (Cl. 172—126)

1

By vibratory pendulums, which are driven by electromagnetic self-interrupters supplied from a source of direct current, there is the drawback that the pendulum, by variation of the working voltage, changes its amplitude and consequently its frequency and impulse-ratio. The term "impulse-ratio" has reference to the ratio between the time during which the contact is closed and the time during which this same contact is open. Owing to this, vibratory pendulums have not been used in many fields, in which the otherwise good properties of said pendulums could assert themselves. As an example of such a field converters of the vibratory type may be mentioned, especially for great loads. By such converters it is as a rule of great importance that the method of operation of the contacts, characterized by frequency and impulse-ratio, should be kept constant by varying working voltage. By motor driven contacts this can be done by known means for keeping the number of revolutions of the motor constant, but with contacts, driven by means of a pendulum it has not until now been possible to eliminate the changes in frequency and impulse-ratio by variation of the working voltage. Furthermore, these changes do not take place continuously by continuous change of the working voltage, but the pendulum runs through several stable and unstable conditions of oscillation, thereby lingering in the stable conditions and passing by leaps through the unstable ones. The pendulum therefor works unreliable and is unfit for the purpose of being a contact converter.

The present invention relates to such vibratory pendulums wherein the voltage for operating the pendulum is supplied from a condenser and the invention will now be described with reference to the drawings in which Figs. 1 and 2 are diagrammatic views of circuit-arrangements embodying the invention, and Fig. 3 is a circuit diagram showing the invention applied to a contact converter.

Referring to the drawings an electromagnet is shown at M for the pendulum P. A switch is illustrated at b which is adapted to be closed by movement of the pendulum and opened during reverse swinging movement of the pendulum. A further contact k is carried by the pendulum P adapted for controlling a circuit extending from a condenser C. An armature A is carried by the pendulum and the armature is operated by the electromagnet M.

The operating voltage for the electromagnet M and accordingly for the pendulum is supplied from the condenser C. The condenser is charged

5 through a resistor R from a source of direct current indicated at E. The voltage of the source of current E is assumed to vary.

The condenser C is discharged over a resistor R, when the contact k engages the associated contact and during the make-interval of the switch k. It will be observed that the discharge of the condenser extends over a longer period when the switch k remains closed over a longer period. Should the voltage across the source E increase and accordingly the voltage across the condenser C will increase and the pendulum will thereby increase its amplitude and consequently the switch k will increase its impulse-ratio. In other words, the interval in which the contacts at k are closed increases and consequently the discharging time for the condenser also increases. Thus the voltage across the condenser C decreases and the voltage in the interval during which the contacts b are closed will hereby within large limits be independent of the voltage of the source E. The magnetic driving power of the electromagnet M on the armature A, and herewith the amplitude of the pendulum, will thus be almost constant.

10 20 25 Fig. 2 shows another simple embodiment. The regulating contact k is here made as a break-contact which, during intervals, the length of which depends on the amplitude of the pendulum, breaks the current supply to the condenser C. Thus a stabilizing effect on the condenser voltage is obtained, and also a nearly constant amplitude for the pendulum.

30 35 Fig. 3 shows another application of the embodiment according to Fig. 2 in a contact converter for converting direct current of one voltage into direct current of another voltage.

The contact converter, containing the transformers T₁ and T₂, the condensers C₁—C₄ and the contacts k₁—k₆, is connected to the same source E of current as the pendulum, and the pendulum operates, besides the self-interrupter contact b and the regulating contact k, also the movable contacts k₁ and k₄ of the converter. A load B is supposed to be connected to the tapping terminals W.

40 45 50 A condition for sparkless breaking and making of all the contacts k₁—k₆ is, that the oscillatory circuits formed by the condensers and the windings of the transformers are tuned in a certain way in relation to the frequency and impulse-ratio of the contacts. Hitherto this condition has been filled only by a certain constant working voltage E; with a pendulum according to the invention, however, such conditions can be filled also by variable working voltage E, since the fre-

quency of the pendulum and so the frequency and impulse-ratio of the contacts $k1$ and $k4$ become constant.

The invention may of course be applied to other technical fields where it is important that the member controlled by the pendulum should have constant frequency.

I claim:

1. In combination, a vibratory pendulum, a controlled electromagnet for vibrating said pendulum, a condenser, a source of direct current, a resistor, a circuit containing said resistor and said source connected in parallel to a discharge circuit for said condenser including said electromagnet and a contact operated by said pendulum for alternatively energizing and deenergizing said electromagnet, a further contact included in a circuit containing said condenser and being adapted to be operated by said pendulum in one of its end positions, and to control the condition of charge of said condenser in dependence on the ratio between the time during which said further contact is closed and the time during which it is broken.

2. In combination, a vibratory pendulum, an electromagnet for vibrating said pendulum, a condenser, a source of direct current, a resistor, a circuit containing said resistor and said source connected in series, said circuit and said condenser being connected in parallel to a discharge circuit for said condenser including said electromagnet and a contact operated by said pendulum for alternatively energizing and deenergizing said electromagnet, a further discharge circuit for said

condenser including a further contact adapted to be operated by said pendulum in one of its end positions and to close said discharge circuit during a moment, the length of which depends upon the ratio between the time during which said further contact is closed and the time during which it is broken.

3. In combination, a vibratory pendulum, an electromagnet for vibrating said pendulum, a condenser, a source of direct current, a resistor, a circuit containing said resistor and said source connected in series, said circuit and said condenser being connected in parallel to a discharge circuit for said condenser including said electromagnet and a contact operated by said pendulum for alternatively energizing and deenergizing said electromagnet, a further contact included in said first mentioned circuit and being adapted to be operated by said pendulum in one of its end positions and to break said first mentioned circuit for a moment, the length of which depends upon the ratio between the time during which said further contact is closed and the time during which it is broken.
